(57) **CLAIM**

We claim the ornamental design for a telephone, as shown and described.

DESCRIPTION

FIG. 1 is a top and front perspective view of a first embodiment of a telephone of the present invention;

FIG. 2 is a front view thereof;

FIG. 3 is a rear view thereof;

FIG. 4 is a first side view thereof;

FIG. 5 is a second side view thereof;

FIG. 6 is a top view thereof;

FIG. 7 is a bottom view thereof;

FIG. 8 is a top and front perspective view thereof shown in an environment of use;

FIG. 9 is a bottom and rear perspective view thereof;

FIG. 10 is a top and front perspective view of a second embodiment of a telephone of the present invention;

FIG. 11 is a front view thereof;

FIG. 12 is a rear view thereof;

FIG. 13 is a first side view thereof;

FIG. 14 is a second side view thereof;

FIG. 15 is a top view thereof;

FIG. 16 is a bottom view thereof;

FIG. 17 is a top and front perspective view thereof shown in an environment of use; and,

FIG. 18 is a bottom and rear perspective view thereof.

In the drawing, the broken lines depict unclaimed environment. The unshaded top portion of the telephone is not part of the claimed design.
